UNITED STATES PATENT OFFICE

PETER E. GELDHOF, OF SYRACUSE, NEW YORK, ASSIGNOR TO SYRACUSE WASHING MACHINE CORPORATION, OF SYRACUSE, NEW YORK, A CORPORATION OF DELAWARE

CENTRIFUGAL CLOTHES DRYING AND RINSING APPARATUS

Application filed August 6, 1927. Serial No. 211,115.

This invention relates to a centrifugal clothes drying and rinsing apparatus involving the use of an upright rotary container for the clothes rotatable about a vertical axis and provided with a foraminous peripheral wall through which the water or other washing or rinsing fluid is expelled by centrifugal force during the rotation of the container and elevated by the same force to any desired level where it is collected and diverted through suitable channels in any lateral direction and discharged into another receptacle or into waste or drainage conduits, as desired.

It is well known that if any fluid per se or held in saturation by an absorbent is confined in a rotary receptacle the fluid will be displaced by centrifugal force from the center outwardly and caused to rise to varying levels according to the speed of rotation along the peripheral wall of the confining medium and the main object of the present invention is to provide simple and efficient means for directing the centrifugally expelled fluid upwardly to any suitable overflow level without the use of pumps or extra fluid impelling means so that it may be discharged from said level into other receptacles or waste conduits by the same centrifugal force.

In other words, I have sought to accomplish this desired uplift of the centrifugal expelled liquid by means of an inverted frustoconical or upwardly-flaring confining medium or baffle shell surrounding the perforated container mainly in radially spaced relation thereto for the purpose of facilitating and accelerating the up-flow of the expelled fluid through suitable outlets and into a collecting trough or chamber from which the fluid may be discharged in any lateral direction desired.

Another object is to provide the collecting chamber or trough with a lateral discharge nozzle or outlet and to support the trough in

such manner that it may be adjusted angularly about the axis of rotation of the container for effecting a corresponding angular adjustment of the discharge nozzle as may be required for discharging the expelled fluid into other receptacles.

Other objects and uses relating to specific parts of the apparatus will be brought out in the following description.

In the drawings:—

Figure 1 is a vertical sectional view of an apparatus embodying the various features of the invention.

Figure 2 is a horizontal sectional view taken in the plane of line 2—2, Figure 1.

As illustrated, this apparatus comprises a main supporting frame which, in this instance, may be made in the form of a circular vat or tub —1— having a central gland —2— in the bottom thereof for receiving a rotary driving shaft —3— which may be connected to any suitable source of power, not necessary to illustrate or describe for rotating the clothes-container.

A ring —4— is mounted upon the upper end of the vat —1— and permanently secured thereto by spot welding, brazing or otherwise to extend upwardly therefrom and thereby to form a bearing for an angular adjustable head or shelf —5— which rests upon the upper edge of the ring —4— in a substantially horizontal plane and is provided with a downwardly extending circular flange —6— journaled within and upon the ring —4— for angular adjustment.

The ring —4— is provided with an inwardly projecting annular flange —7— upon which the lower edge of the flange —6— is adapted to rest.

An annular retainer ring —8— is secured or otherwise secured to the inner face of the flange —6— to extend downwardly across the inner face of and under the flange —7— to hold the head or shelf —5— against upward

displacement without interfering with its free angular movement.

The portion of the head or shelf —5— immediately above the annular flange —6— is provided with outward and inner annular flanges —9— and —10— projecting upwardly therefrom in radially spaced relation to form an annular trough or collecting chamber —11— having a laterally and outwardly extending discharge nozzle —12— tangential thereto for directing the discharge fluid from the trough into another receptacle or into a waste pipe as may be desired.

This head or shelf is also provided with a laterally extending drain board —5'—, Figure 2, adjacent the nozzle —12— as shown in Figure 2, adapted to extend over the top of an adjacent tub —A— of a clothes washing machine with which the centrifugal drier is preferably associated to facilitate the transfer of clothes from the washing machine to the drier and also to drain the washing fluid back into the tub during such transfer.

The outer annular flange —9— is provided with a laterally and upwardly extending offset annular ledge —13— for receiving and supporting a cover plate —14— which is preferably hinged at —15— to said offset to swing about a horizontal axis to and from a position across the top of the tub —1— and collecting chamber —11—.

Associated with the shelf —5— and its collecting chamber or trough is the means for carrying out the main object of the present invention, said means consisting in this instance of an outer upright imperforate shell —16— and an inner upright foraminous shell or basket —17— adapted to receive the clothes from which the washing fluid is to be extracted by centrifugal force.

As illustrated, the shells —16— and —17— are co-axial and concentric and are united at their lower ends and provided with an imperforate bottom wall common to both shells, but obviously may be otherwise united if desired without departing from the spirit of this invention, the remaining superposed portions of the shells being arranged in spaced relation to form an intervening chamber —19— for receiving the washing fluid expelled from the clothes by centrifugal force when the shells are rotated in a manner hereinafter described.

These shells constitute what may be broadly termed a receptacle for the clothes and washing fluid and are adapted to be removed or reinserted as a unit through the open upper end of the tub —1— and head —5— when the cover —14— is opened and when placed in operative position within the tub and head extend from a level near the bottom of the tub some distance above the bottom of the head —5— in concentric spaced relation thereto with just sufficient clearance between the outer shell —16— and inner periphery

of the tub —1— and head —5— to avoid friction therewith.

The driving shaft —3— extends some distance above the bottom of the tub —1— for receiving and supporting the outer and inner shells —16— and —17— co-axial therewith.

The bottom —18— of the receptacle comprising the shells —16— and —17— is provided with a central hub —20— having a central angular socket —21— for receiving the angular upper end —3'— of the driving shaft —3— to impart rotary motion to the receptacle as the shaft —3— is rotated and also to permit upward displacement of the receptacle from the driving shaft when it is desired to remove the receptacle from the tub for cleansing or other purposes.

The inner receptacle —17— is preferably cylindrical and provided with a perforated peripheral wall extending from the bottom —18— to approximately the level of the upper end of the inner flange —10— of the head —5—.

The outer shell —16— is preferably made in the form of an inverted truncated cone tapered from top to bottom and having its lower end united to the periphery of the bottom —18— and adjacent lower end of the shell —17— and its remaining portion flaring upwardly and extended to a level slightly above the upper edge of the inner flange —10— of the head —5— and therefore in spaced relation to the periphery of the inner shell —17—, the upper end of the shell —16— being provided with an out-turned flange —16'— for directing the upwardly flowing fluid into the collecting trough —11—.

The upper end of the inner shell —17— is provided with an out-turned flange —23— terminating against the inner face of the adjacent portion of the shell —16— and provided with a series of peripheral recesses —24— to allow the washing fluid expelled by centrifugal force from the clothes in the container —17— to overflow therethrough into the collecting chamber or trough —11—.

When the wet or damp clothes are placed within the perforated cage or container —17— through the open upper end thereof and both shells are rotated by the rotation of the driving shaft —3— the washing fluid or moisture present in the clothes will be expelled by centrifugal force through the perforated peripheral walls of the shell —17— into the chamber —19— and against the upwardly flaring peripheral wall of the outer shell —16— which serves as a baffle to confine and direct the fluid upwardly through the overflow passages —24— over the flange —20— and into the collecting chamber —11— from which it is expelled by the same force through the nozzle —12— into another receptacle or waste pipe as may be desired.

It will be observed that the upward flare of the outer shell —16— and its angular rela-

tion to the cylindrical wall of the shell —17— gradually increases the capacity of the chamber —19— from bottom to top thereby allowing ample space for the up-flow of the washing fluid along the upwardly flaring walls 5 of the shell —16— which, by reason of its upward and outward inclination, not only directs the centrifugally expelled water upwardly and outwardly through the overflow 10 passages —24— but also greatly facilitates and accelerates such discharge thereby reducing the load upon the driving motor.

The cover —14—, when closed, fits snugly against the upper edge of the outer wall —9— of the collecting chamber —11— to prevent leakage of the expelled fluid at the joint, said cover being also provided with a downwardly projecting annular flange —25— having its lower edge in close proximity to the upper 15 edge of the flange —23— just at the inside of the discharge openings —24— to prevent the passage of the water from said discharge openings back into the container —17—.

A lid —26— is journaled at —27— upon 20 the central portion of the cover —14— to move therewith into and out of frictional engagement with the upper end of the container —17— as the cover —14— is closed and opened to rotate with said container and 25 also to hold the upper end of both shells —16— and —17— against upward or lateral displacement or vibration, it being understood that the journal bearing —27— is coaxial with the axis of the driving shaft —3—.

30 A perforated rinsing tube —22— similar to that shown in my pending application Serial No. 205,170, filed July 12, 1927, has its lower end removably seated in a socket in the upper end of the hub —20— and its upper 35 end extended to approximately the level of the lid —26— and open at the top for receiving a rinsing fluid which may be introduced thereinto through a supply tube —28—.

The tube may be connected to any available 40 source of supply for the rinsing fluid and preferably extends through a tubular nipple —29— which in turn is secured to the lid —26— and extends through registering openings in said lid and cover —1— as shown 45 in Figure 1.

Operation

When it is desired to dry wet or damp 50 clothes the cover —14— with the lid —26— thereon are first opened after which the wet clothes are placed within the container —17— to any desired height below the top of the container.

The cover —14— and lid —26— are then 55 closed and locked in place by any suitable locking mechanism as, for example, that shown in the joint application of Geldhof and Papworth, Serial No. 138,295, filed Sept. 28, 1926, after which the receptacle including 60 the perforated basket —17— and tapered

shell —16— are rotated at sufficient speed to cause the expulsion of the moisture from the clothes through the perforations of the container —17— and against the peripheral wall of the tapered shell —16—.

70

The upward and outward inclination of the shell —16— causes the centrifugally expelled water to be deflected upwardly and outwardly through the overflow passages —24— and thence into the collecting chamber —11— from which it is delivered or discharged through the nozzle —12— into any other receptacle or waste pipe, it being understood that the nozzle may be adjusted angularly about the axis of the receptacle to 80 discharge the fluid in any lateral direction.

75

What I claim is:

1. In a centrifugal clothes drier, a rotary container for the clothes having a vertical foraminous peripheral wall, and a shell including an axially tapered imperforate wall extending circumferentially around the foraminous wall of the container and rigidly connected thereto for deflecting the expelled fluid toward the larger portion of the shell 85 away from the container, a collecting trough communicating with the larger end of the shell for receiving the expelled fluid therefrom, a flange associated with the upper ends of the two walls for directing fluid into the 90 trough, and means for rotating the container.

95

2. In a centrifugal clothes drier, a rotary container for the clothes having a vertical foraminous peripheral wall, and an axially tapered imperforate wall extending circumferentially around the foraminous wall of the container and rigidly connected thereto for deflecting the expelled fluid toward the larger portion of the shell away from the container, a discharge conduit receiving the fluid from the larger end of the shell and adjustable about the axis thereof for discharging the fluid in different directions, means for directing the fluid between the walls into the conduit, and means for rotating the container. 100

105

3. In a centrifugal clothes drier, a container rotatable about a vertical axis and provided with a vertical foraminous peripheral wall, an upwardly flaring imperforate shell extending circumferentially around the foraminous wall of the container and rotatable therewith, said shell having an overflow outlet near its larger end, a second shell supported independently of the first named shell and provided with a circumferentially extending trough for receiving fluid from said outlet, and a flange associated with the upper ends of the two shells for directing fluid into the overflow outlet, and means for rotating the container. 115

115

4. In a centrifugal clothes drier, a container rotatable about a vertical axis and provided with a vertical foraminous peripheral wall, and an upwardly flaring imperforate shell extending circumferentially around the 120

120

shell —16— are rotated at sufficient speed to cause the expulsion of the moisture from the clothes through the perforations of the container —17— and against the peripheral wall of the tapered shell —16—.

125

130

foraminous wall of the container and rotatable therewith, said shell having an overflow outlet near its larger end, a second shell supported independently of the first named shell and provided with a circumferentially extending trough for receiving fluid from said outlet, and an upwardly inclined flange between the foraminous wall and imperforate shell for directing fluid into the overflow outlet, and means for rotating the container.

10 In witness whereof I have hereunto set my hand this 4th day of August, 1927.

PETER E. GELDHOF.
